UNITED STATES PATENT OFFICE.

WILLIAM L. BLYTHE, OF MOKELUMNE HILL, CALIFORNIA.

PICK.

SPECIFICATION forming part of Letters Patent No. 258,276, dated May 23, 1882.

Application filed February 18, 1882. (No model.)

To all whom it may concern:

Be it known that I, WILLIAM L. BLYTHE, of Mokelumne Hill, county of Calaveras, State of California, have invented an Improved Pick; 5 and I hereby declare the following to be a full, clear, and exact description thereof.

My invention relates to that class of picks in which the blade and stock are made separate; and it consists in a novel means of securing the blade to the stock or handle, whereby it may be easily secured or removed when necessary.

Referring to the accompanying drawings, Figure 1 is a view of my pick. Fig. 2 shows 15 the different parts separated.

Let A represent a handle, having bolted to its end a metal strip, B, forming an eye or socket, as shown.

Let C represent the blade, having a point at 20 each end and curved appropriately. On its outer or concave surface, about the middle, is a notch, a, in which the strip B fits when the blade is inserted in the eye formed by said strip. This causes the strip B to lie flush with 25 the blade, as well as to afford security, as hereinafter shown. Upon the concave surface of the blade is cut a slight notch, b.

D represents a key, wedge-shaped, of a length to fit within the notch b. Upon the sides of 30 the key D, at its smaller end, are lugs or projections c. This key is fitted into the eye formed by strip B, and lies within the notch b of the blade, its side lugs, c, fitting against the edges of the strip.

In one edge of the key D is formed a recess, in which a spring, e, is secured by one end. Its other end is provided with a large head, e', 35 that may catch behind the edge of the strip B.

The spring may be pressed down within its 40 recess, and its head will lie flush with the key and present no obstruction to the key in passing through the eye. When this key is pushed

through the eye of strip B, and it reaches its limit by reason of the lugs c, the head e' of the spring e will spring out to fit against the edge 45 of said strip, thus preventing the key from moving from side to side.

E represents another key, wedge-shaped, which is inserted within the eye between key D and the handle.

The eye formed by the strip B is just large enough to receive the blade and the two keys. The keys D E have their inclinations in reverse directions, so that they wedge each other.

The notches a b in the blade render it firm 55 against the strip B and key D. When struck on one point the blade cannot be forced out, because the lugs or projections c on key D press against the edge of strip B and will not allow the key to move. When struck upon the other 60 point the blade cannot move, both because of the head e' of spring e in key D and because said key is wedged against key E, which is itself wedged firmly in the eye.

In order to remove the blade the key E is 65 first loosened by knocking, and is taken out. The spring e is then pressed down, and key D may be taken out, when the blade may also be removed.

Having thus described my invention, what I 70 claim as new, and desire to secure by Letters Patent, is—

In a pick, the strip B, secured to the handle and forming a socket or eye, in combination with the blade C, having notches a b, wedge 75 D, with its lugs c, and spring e, having a head, e', and the wedge E, all arranged to secure the blade within the eye, substantially as described.

In witness whereof I hereunto set my hand.

W. L. BLYTHE.
